UNITED STATES PATENT OFFICE

PERRY J. SWEENEY, OF WHITING, INDIANA, ASSIGNOR TO STANDARD OIL COMPANY,
OF WHITING, INDIANA, A CORPORATION OF INDIANA

BUBBLE TOWER

Application filed May 13, 1927. Serial No. 191,250.

This invention relates to improvements in fractionating columns and particularly to columns of the bubble cap type.

The invention will be readily understood 5 from the following description taken in conjunction with the drawings, in which:

Figure 1 is an elevational view of a column partly broken away to show plates and associated parts; and

10 Fig. 2 is a sectional view of the improved overflow pipe on an enlarged scale.

Referring to the drawings, 10 is a fractionating column provided with bubble plates 11 of the ordinary type. The column 15 is provided at its lower end with a vapor supply pipe 12 and a liquid draw-off pipe 13, and at its upper end with a liquid supply pipe 14 and a vapor outlet 15.

Instead of the ordinary overflow pipes 20 which are mounted on each bubble plate and extend into the liquid maintained on the bubble plate next below I provide overflow pipes 16 which contain a liquid seal or trap and are provided with an outlet located 25 above the liquid level of the plate next below.

Each of the overflow pipes 16 preferably comprises an upstanding nipple 17, a flange 18 therebeneath for attachment to a bubble cap plate, and a lower body portion constituted by sides 19 and a wall portion 20 which extends downwardly from said flange, closes the bottom of the nipple 17 and then proceeds upwardly forming with the sides 19 a well 21. The wall 20 then bends downwardly again and together with extensions of the sides 19 forms a spout 22 which terminates somewhat above the level of the liquid maintained in the next inferior plate. A septum 23 extends between the sides 19 and from the 35 flange 18 into the well 21 so as to establish a liquid seal therein. The septum 23 preferably converges downwardly towards the vertical part of the wall portion 20 so as to create a scavenging effect in the well 21 thus 40 aiding in preventing accumulation of rust or scale therein.

As shown in the drawings, the overflows 45 16 are attached to the bubble plates 11 at a point near the margins thereof. It is preferred to place the overflows 16 at opposite

points on alternate bubble plates. The liquid sealed spouts 18 extend toward the central portion of each of the bubble plates 11. By means of this structure the overflow devices of the present invention pick up the 55 liquid on their respective bubble plates at a point adjacent the margin thereof, and discharge it centrally of the bubble plate therebeneath and above the level of the liquid thereon. By means of this structure, a substantially uniform composition is realized 60 for the pools of liquid maintained on the bubble plates and consequently more accurate vapor fractionation is possible.

Although the present invention has been 65 described in connection with the details of a specific embodiment thereof, it is not intended that such details shall be regarded as limitations upon the scope of the invention except in so far as included in the accompanying claims.

I claim:

1. A bubble tower provided with superimposed bubble cap plates, the successive bubble-cap plates being provided with overflow 75 pipe plates, each comprising a nipple projecting above the bubble plate to which it is attached near the margin thereof, a spout below the plate and emptying centrally above the level of liquid on the plate beneath, 80 whereby a flow of liquid is established from the central portion to the margin of said plates and means providing a liquid seal between said overflow and the spout.

2. A bubble tower provided with superimposed bubble cap plates, the successive bubble-cap plates being provided with overflow pipes for said bubble cap plates, each comprising a nipple projecting above the bubble plate to which it is attached near the margin 90 thereof, a well portion, a spout extending therefrom and emptying centrally above the level of liquid on the plate beneath, whereby a flow of liquid is established from the central portion to the margin of said plates and 95 means providing a liquid seal in said well portion.

In testimony whereof I have hereunto set my hand this 10th day of May, 1927.

PERRY J. SWEENEY. 100
